E. J. Morin, Inventor

By *A. Knudsen Jr.* Attorney

UNITED STATES PATENT OFFICE.

EDWARD J. MORIN, OF WYNOT, NEBRASKA.

POCKET PENCIL-HOLDER.

1,401,809.

Specification of Letters Patent. Patented Dec. 27, 1921.

Application filed March 1, 1921. Serial No. 448,804.

To all whom it may concern.

Be it known that I, EDWARD J. MORIN, a citizen of the United States, residing at Wyo, in the county of Cedar and State of Nebraska, have invented certain new and useful Improvements in Pocket Pencil-Holders; and I do hereby declare the following to be a full, clear, and exact description of the invention, such as will enable others skilled in the art to which it appertains to make and use the same.

The invention relates to holders for retaining pencils, pens and analogous articles in the pocket against accidental displacement and comprising a clip to engage the upper edge of the pocket or like part and one or more receivers for the pencil or like article to be retained in position.

The invention provides a device of this character which facilitates the placing of the pencil in the receiver and which prevents the casual displacement thereof, the end of the receiver being flared to direct the pencil therein and a spring retainer operating with the receiver to hold the pencil or like article therein.

Other objects and advantages will be apparent and suggest themselves as the nature of the invention is understood.

While the drawings illustrate an embodiment of the invention, it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a perspective view of the holder,

Fig. 2 is a perspective view of the clip,

Fig. 3 is a perspective view of the receiver member,

Fig. 4 is a vertical transverse section on the line $\alpha-\alpha$ of Fig. 1, and

Fig. 5 is a vertical section through the

clip and the receiver showing more clearly the relation of the spring retainer.

Corresponding and like parts are referred to in the following description and 50 designated in the several views of the drawings by like reference characters.

The device comprises essentially two parts or members each being formed of sheet metal of proper gage and temper. The 55 members or parts, after being cut or stamped from the sheet metal, are bent to the required shape substantially as shown in the accompanying drawings.

The clip comprises a base plate 1 and a 60 hook 2, and is formed from an elongated blank folded upon itself. The hook 2 has a portion cut therefrom for lightness and to give added resiliency. Slits or cuts 3 are formed in opposite edge portions of the plate 1 to provide for connecting the two parts or members in a manner presently to be described. Spring retainers 4 are partly cut from the plate 1 and pressed outwardly to coat with the receivers for holding the 70 pencils or analogous articles in position against casual displacement.

The receiver member comprises a plate crimped, corrugated or fluted, as indicated at 5, which coats with the plate 1 to provide receivers for holding the pencil, pen or other article. The ends of the plate are formed with extensions 6 which are adapted to pass through the slits or cuts 3 and secure the two members or parts, when assembled, by being bent or clenched against the rear side of said plate 1. The upper or entrance ends of the receivers 5 are flared, as indicated at 7, to facilitate the entrance of pencils and like articles therein. The spring retainers 4 and receivers 5 are in coincident position, whereby to provide a retainer for each of the receivers to hold the articles therein against casual displacement.

The parts comprising the holder are separately formed and when brought together the extensions 6 of the receiver member

register with the slits or cuts 3 of the clip member so as to pass therethrough, the parts thus assembled being made secure by bending or clenching the extensions 6 against 5 the rear side of the plate 1.

What is claimed is:

A pocket pencil holder comprising a clip including a plate having slits adjacent its opposite edge portions and having spring 10 retainers forming a part thereof, and a receiver member comprising a fluted or crimped plate and having terminal exten-

sions to pass through the said slits and clenched against the rear side of the clip plate, the receiving ends of the crimped or 15 flutes being outwardly flared to facilitate the entrance of articles therein.

In testimony whereof I affix my signature in presence of two witnesses.

EDWARD J. MORIN.
